[57] CLAIM

The ornamental design for a lighting fixture, as shown and described.

DESCRIPTION

FIG. 1 is a bottom perspective view of a lighting fixture in accordance with our new design, in which corner connectors are shown in broken lines;

FIG. 2 is bottom perspective view thereof, in which the corner connectors shown in FIG. 1 have been omitted to reveal portions of the design obscured by the corner connectors;

FIG. 3 is a bottom plan view thereof;

FIG. 4 is a front elevational view thereof, the rear and side elevations being identical thereto;

FIG. 5 is a bottom perspective view of another embodiment of a lighting fixture in accordance with our new design, in which corner connectors are shown in broken lines;

FIG. 6 is bottom perspective view thereof, in which the corner connectors shown in FIG. 5 have been omitted to reveal portions of the design obscured by the corner connectors;

FIG. 7 is a bottom plan view thereof; and,

FIG. 8 is a front elevational view thereof, the rear and side elevations being identical thereto.

The broken lines are shown in FIGS. 1, 3, 5, and 7 for illustrative purposes only and indicate the nature and use of our new design.
